[57] CLAIM

The ornamental design for an instant food cube package, as shown and described.

DESCRIPTION

FIG. 1 is a perspective view of an instant food cube package showing my new design;

FIG. 2 is a front elevational view thereof, the undisclosed rear being a mirror image;

FIG. 3 is a left side elevational view thereof, the undisclosed right side being a mirror image;

FIG. 4 is a top view thereof; and,

FIG. 5 is a bottom view thereof.

The rear view is a mirror image of FIG. 2, and the right side view is a mirror image of FIG. 3.
